UNITED STATES PATENT OFFICE.

LOUIS FALZER AND EDWIN M. WEBBER, OF CHICAGO, ILLINOIS, SAID WEBBER AS-SIGNOR TO SAID FALZER.

HOISTING MACHINE.

Application filed August 18, 1922. Serial No. 582,607.

To all whom it may concern:

Be it known that we, LOUIS FALZER and EDWIN M. WEBBER, citizens of the United States, residing at Chicago, in the county of Cook and State of Illinois, have invented certain new and useful Improvements in Hoisting Machines, of which the following is a specification.

This invention relates to improvements in power-operated hoisting machines, and has reference more particularly to a machine for hoisting dirt from caisson and other wells.

In the digging of caissons for the foundations of large buildings, it has heretofore been the universal practice, wherever power-actuated hoists were employed, to equip the mouths of a row of caissons with winch-heads and pulleys, and operate them all simultaneously through a cable engaged with the pulleys of all the hoists and itself driven by a motor at one end of the row. Such a method of power operation is practical and economical only where the excavation proceeds with substantial uniformity throughout the entire group of caissons; but it very frequently happens that the work in one or more is delayed through encountering abnormal conditions, so that with this method a large amount of unnecessary power is expended idly and much time is wasted.

One object of our present invention is to provide a simple, inexpensive, and practical portable machine which operates as a unit on an individual caisson or well, and as soon as the latter is dug can be readily moved into position to assist in the digging of another.

Another object of the invention is to provide a hoisting apparatus for raising lowered buckets wherein the machine, and particularly the winch-head shall be so positioned as to be out of the way of the bucket as it drops into and rises out of the caisson or well. A further object is to provide a machine wherein the winch-head may be continuously rotated in one direction only, while the hoisting cable may be so manipulated on the winch-head by the operative as to expeditiously effect the alternate lifting and lowering operations without any stopping or reversing of the motor or winch-head.

Other objects and attendant advantages of the invention will be apparent to persons skilled in the art as the same becomes better

understood by reference to the following detailed description, taken in connection with the accompanying drawings wherein we have illustrated an embodiment of the invention which has been found in practice to satisfactorily effectuate the above-stated purposes and objects of the invention, and in which—

Fig. 1 is a side elevation of the apparatus shown as mounted in working position at the upper end of a caisson or well; and

Fig. 2 is a similar view at right angles to that of Fig. 1 and viewed from the left of the latter figure.

Referring to the drawings, 5 indicates the well or hole of the caisson, the dirt and other débris from which is raised by the bucket 6. On a suitable foundation 7 surrounding the mouth of the hole 5 is erected a tripod 8 having its apex approximately in the line of the center or axis of the hole 5.

Swung from the top of the tripod by a suspension rope or cable 9 is a pulley block 10 in which is journaled a grooved pulley or sheave 11, over which is passed a rope or cable 12 attached at its lower end to the bail 6' of the bucket 6. From the sheave 11 the cable extends downwardly to and around the winch-head 13 of the hoisting machine. This latter, as herein shown, comprises an electric motor 14, a speed reducer 15, a flexible coupling 16 between the motor shaft and the speed reducer, an ordinary safety device 16' for preventing breakage of parts in the event of abnormal load strains, and the winch-head 13 equipped at its inner end with a rope guard 17; also an outboard bearing and pedestal 18 supporting the bearing for the winch-head shaft.

The above parts are all mounted upon and supported by a base-plate 19, preferably consisting of a section of channel bar; and this latter in turn rests upon a pair of horizontal brace-bars 20 attached to and extending between a pair of the tripod legs; the base-plate 19 being strongly anchored in place by bolts 21 extending therethrough, between the cross-bars 20, and also through the cross-bars 22 underlying the bars 20.

At its outer end the base-plate 19 is adjustably supported from the ground or foundation member 7 by and between a pair of legs 23; these latter being provided adjacent to their upper ends with a series of spaced bolt holes 24 to receive fastening bolts 25.

passed through the sides of the channel beam support 19. Diagonal brace-bars 26 and 27 connect the opposite sides of the base-plate 19 with the supporting bars 20 and the legs 23, respectively.

It will be observed that the cable winding parts of the machine are so disposed that the winch-head 13 lies well to one side of the center of the hole, so as to avoid interference with the bucket as the latter is raised. This necessitates the disposition of that limb of the hoisting cable which lies between the sheave 11 and the winch-head 13 at a slight angle to the vertical; and to maintain this section of the winding cable at a right angle to the axis of the winch-head, the latter and its motor, speed reducer and safety device, which are all in axial alignment with each other, are correspondingly inclined to the horizontal, as clearly shown in Fig. 1, and the axis of the winch-head is also disposed approximately radial to the vertical path of travel of the bucket.

In the operation of the apparatus, the machine attendant, standing just at the left of the hole in Fig. 1, wraps the cable 12 around the winch-head 13 with a sufficient number of coils to insure ample friction, and as the winch-head is turned to wind up the cable, the attendant simultaneously pulls on the free end of the cable with sufficient force to maintain the friction grip of the coils on the surface of the winch-head, a comparatively light pull being sufficient where a considerable number of turns of the cable around the winch-head are taken. As the bucket emerges from the hole, it is grasped by one or more attendants, emptied, and then swung back to a position directly over the hole. The machine attendant, without stopping the motor, intermitts his pull on the cable, and pays the latter out slightly, thereby releasing the friction grip of the cable on the winch-head, and the bucket descends by gravity. An important advantage, already above referred to, resides in the fact that the winch-head lies to one side of the vertical path of travel of the bucket so that it does not interfere with the manipulation of the latter during the elevating, dumping and replacing operations. Another advantage of the described apparatus resides in its portable character, since, as soon as one hole has been dug to the required depth, the entire apparatus can be picked up bodily by three men, one at each leg of the tripod, and transported to a position over the next hole to be dug.

We have herein shown and described one practical embodiment of the invention for

purposes of illustration, but it is manifest that the details of structure and arrangement may be considerably modified and varied without departing from the principle of the invention or sacrificing any of its advantages. Hence, we reserve all such variations and modifications as fall within the spirit and purview of the appended claims.

We claim:

1. In a portable hoisting apparatus of the character described, the combination of a pulley-supporting frame, a pulley suspended from and within the upper portion of said frame, a hoisting cable passed over said pulley, a bucket hung from one depending limb of said cable, a platform mounted on the lower portion of said frame, an electric motor, speed reducer, safety device and winch-head mounted in coaxial alignment on said platform with said winch-head disposed at one side of the vertical path of said bucket and having the other depending limb of said cable coiled thereon, and the axis of rotation of said winch-head being disposed substantially at right angles to the depending limb of the cable wound thereon.

2. In a portable hoisting apparatus of the character described, the combination of a tripod, a pulley suspended from the apex of said tripod, a hoisting cable passed over said pulley, a bucket hung from one depending limb of said cable, a cross-bar connecting two legs of said tripod, a platform mounted on said cross-bar, and a winch-head and a motor therefor mounted on said platform with said winch-head disposed at one side of the vertical path of said bucket and receiving the other depending limb of said cable coiled thereon, the axis of said winch-head being downwardly and forwardly inclined to lie at substantially a right angle to the depending limb of the cable wound thereon.

3. In a portable hoisting apparatus of the character described, the combination of a tripod, a pulley suspended from the apex of said tripod, a hoisting cable mounted on said pulley, a bucket suspended from one depending limb of said cable, a cross-bar connecting two legs of said tripod, a platform mounted on and attached to said cross-bar, a leg support for the outer end of said platform, and an electric motor, speed reducer, safety device and winch-head mounted in coaxial alignment on said platform with said winch-head disposed at one side of the vertical path of said bucket and having the other depending limb of said cable coiled thereon.

LOUIS FALZER.
EDWIN M. WEBBER.
